UNITED STATES PATENT OFFICE

WILLIAM F. OBERHUBER, OF LANSOWNE, PENNSYLVANIA, ASSIGNOR TO FRANKLIN DEVELOPMENT COMPANY, OF PHILADELPHIA, PENNSYLVANIA, A CORPORATION OF PENNSYLVANIA

RUBBER SLUG FOR CONDENSER TUBES

Application filed February 2, 1926. Serial No. 85,533.

My invention relates to slugs for cleaning condenser tubes and the like, to be driven through the tubes preferably by compressed air or water.

5 A purpose of my invention is to interiorly flare the forward end of a rubber slug in order to increase the tightness with which it fits a tube through which it is being driven and to discharge the driving fluid through 10 the tube and against tube deposit to the best advantage.

A further purpose is to internally flare the rear end of the slug so as to swell it against the tube by the driving fluid, flaring it preferably to a lesser extent than the forward end.

A further purpose is to internally rifle the bore of a rubber slug in order to make its action more effective.

20 A further purpose is to internally wedge a rubber slug to expand it against a tube.

Further purposes will appear in the specification and in the claims.

I have preferred to illustrate my invention 25 by one main form only, with minor modifications, and have selected a form that is practical, efficient, inexpensive, simple in manufacture, and that at the same time well illustrates the principles involved.

30 Figure 1 is a fragmentary longitudinal section of a tube and a slug in the tube.

Figure 2 is a side elevation of the slug seen in Figure 1.

Figure 3 is an end elevation of Figure 2.

35 Figure 3a is an end elevation of the structure sectioned in Figure 4.

Figures 4, 5, 6 and 8 are longitudinal sections showing modified forms.

Figure 7 is a section of Figure 4 upon line 40 7-7.

In the drawings similar numerals indicate like parts.

Describing in illustration and not in limitation, and referring to the drawings:

45 Prior to my present invention slugs of rubber or elastic material have been used for cleaning condenser tubes and the like, of which a number of forms are shown in my applications No. 748,435, auxiliary spring plugs 90 for condenser tubes, and No. 572,570 for

method and apparatus for cleaning condenser tubes.

I have discovered that it is quite advantageous to internally bell or flare the forward end of the slug forwardly and that when this is done the contact between the front portion of the slug and a tube through which it is being driven is very much more close than when the slug is not thus forwardly flared. This tight gripping between the circumferential forward end of the slug and the internal surface of the tube through which it is being driven is doubtless due to longitudinal compression throughout the body of the slug resulting from driving the slug through the tube against resistance at the circumference offered by dirt of the tube.

In bellng or flaring the forward end of the tube I am able to secure another and marked advantage illustrated in Figures 1-4 by suit- 70 ing the bell or flare to nozzle purposes, enlarging it forwardly so as to apply the driving fluid as abruptly as possible against the interior of the tube at or shortly in advance of the forward outer edge of the slug.

This nozzle is particularly advantageous when air or other gas or vapor is used as a driving fluid because of the continued expansion and acceleration of the gas or vapor, which strikes the interior of the tube at high 80 velocity and cuts the deposit at the edge or in advance of the passage of the slug or both according to the flare and the pressure as is well understood in arts using expanding nozzles.

85 Independently of this action the blast of fluid through the slug tends to clear out the deposit which has been loosened so as to relieve against clogging of the tube.

I also desirably internally flare the rear 90 end of the slug rearwardly but preferably to a lesser extent than the forward end. This internal flare of the rear end of the slug serves the double purpose of permitting fluid pressure within the rearward cupped portion to 95 expand the elastic material of the slug against the tube, and of making the approach to the opening through the slug more nearly that proper for a nozzle.

100 Referring to the figures:—The slug prefer-

ably comprises a single homogeneous mass of molded rubber 8. The forward interiorly flared end takes the form of an expanding nozzle for high pressure air or other expanding fluid. The diameter at the forward end is preferably slightly greater than that of the tube 9 in which the slug is designed to be used.

As the slug is driven through the tube the material throughout the length of the slug is 10 compressed by reason of the resistance offered to its motion by friction against the tube interior and by engagement at 10 with the dirt within the tube. As the resistance at the front edge presses the slug rearwardly the 15 driving fluid presses it forwardly resulting in strong outward pressure against the surface of the tube, and corresponding greater friction against the tube and more effective cleaning.

20 The same slug reversed will go through the tube relatively easily while even through a clean tube when being driven in the direction indicated by the arrow I find that the contact between the forward end and the inner 25 surface of the tube is a very strong one.

In the form shown in Figures 3a and 4 I internally rib or groove the bore of the slug at 11 as in rifling giving the rib or groove a spiral form for the double purpose of causing 30 rotation of the slug and of more effectively distributing the driving fluid against the interior of the tube.

Obviously the outward pressure against the tube is greatly increased by the pressure of 35 the driving fluid. This pressure is greatest at the rear end and progressively diminishes forwardly along the bore of the slug.

40 The advantageous forward flaring may be used to obtain additional friction whether or not the slug be longitudinally perforated, and this is illustrated in Figures 5 and 6.

Though I prefer to have the slug longitudinally perforated and flared rearwardly to effect tight expansion against the tube at 45 the rear end of the slug as well as flaring forwardly to permit longitudinal compression responsive to resistance offered upon the outer circumference of the slug, I show in Figure 6 a form in which both the rearward cupping 50 and the longitudinal perforation have been omitted.

The aperture 12 and particularly the flare of the opening at the rear of the aperture facilitates the expansion of the central part 55 of my slug against the tube whether the forward end of the slug be belled to increase the pressure there or not. I have already pointed out that the pressure of the fluid tends to expand the entire slug and that the bellying 60 of the rearward portion of the slug increases the effectiveness of this expansion at the rear end. In Figures 4, 7 and 8 I show mechanical means for expanding the central part of the slug in a wedge 13. The wedge is also 65 shown in Figure 7.

In the form of Figure 7 the wedging takes place at an interior point 14 only and the presence of the ribs 11 permits passage of driving fluid through a portion of the opening 12', notwithstanding the presence of the 70 wedge. Spiral streams of driving fluid pass through outside the wedge.

In the form shown in Figure 8 the wedge 13' is forced by the fluid pressure into a different opening 12' which tapers throughout 75 nearly the whole length of the slug permitting expansion of an otherwise solid slug body throughout substantially its entire length. By the shape of the rear end of the wedge 80 the rear of the flare of the slug will also be expanded.

In this form of Figure 8 the expanding operation is almost wholly mechanical.

In view of my invention and disclosure variations and modifications to meet individual whim or particular need will be evident to others skilled in the art which will attain all or a part of the benefit of my invention without copying my illustrations and I therefore claim all such in so far as they fall within the reasonable spirit and scope of my invention.

Having thus described my invention, what I claim as new and desire to secure by Letters Patent is:—

1. A longitudinally perforated rubber slug for cleaning condenser tubes and the like, said perforation internally flaring toward the forward and rearward ends of the slug.
2. A longitudinally perforated rubber slug for cleaning condenser tubes and the like, the perforation flaring toward the forward end.
3. A slug for cleaning condenser tubes and the like, having a longitudinal perforation, said perforation flaring toward the front and toward the rear, the forward flare being longer than the rearward.
4. A perforated rubber slug for cleaning condenser tubes and the like, internally rifled to make it rotate during its passage through a condenser tube.
5. A rubber slug for cleaning condenser tubes and the like, having a longitudinal perforation, said perforation flaring forwardly and rearwardly and having rifling upon its interior.
6. A rubber slug for cleaning condenser tubes having a central tapered opening in combination with a wedge fitting in the opening and adapted to be driven into it by the operating fluid to spread the slug against the interior of the condenser tube.
7. A device of the character described comprising a rubber slug having end walls and also having side walls adapted for engagement with the inner walls of condenser tubes, there being an opening through the slug between the end walls, and a plug having a dimension larger than a minimum dimension

sion of the opening, inserted in the opening with the cross sections of the slug opening and the plug not in registering relation, whereby upon fluid propulsion of the device, the plug expands the slug and the driving fluid passes through the slug.
